(57) **CLAIM**

The ornamental design for an airplane, as shown and described.

DESCRIPTION

FIG. 1 is a right side, top, front, perspective view of an airplane showing my new design;

FIG. 2 is a left side view thereof;

FIG. 3 is a right side view thereof;

FIG. 4 is a top view thereof;

FIG. 5 is a bottom view thereof;

FIG. 6 is a front view thereof; and,

FIG. 7 is a rear view thereof.

The characteristic feature of the design is the surface ornamentation on the fuselage, jet engine, and tail of the airplane. The stippling represents a contrasting appearance that contrasts with the remainder of the airplane.

The characteristic feature of the design is the surface ornamentation on the fuselage, jet and tail of the airplane. The stippling illustrates a color contrasting with the color of the remainder of the airplane.
